(57) CLAIM

The ornamental design for a bottle, as shown and described.

DESCRIPTION

FIG. 1 is a front, left perspective view of a bottle; FIG. 2 is a right side elevational view thereof, the opposite side being substantially a mirror image thereof;

FIG. 3 is a top plan view thereof;

FIG. 4 is a bottom plan view thereof; and,

FIG. 5 is a rear elevational view thereof.

The pirate forming a part of the claimed design is a registered trademark of Joseph E. Seagram & Sons, Inc.
